QUICK ACTION WHIP STOCK

Clinton L. Walker, Piedmont, Calif.

Application December 5, 1936, Serial No. 114,448

5 Claims. (Cl. 255—1)

This invention relates to the drilling of oil wells and particularly pertains to whipstocks for offset drilling.

It is the principal object of the present invention to provide an improved whipstock which can be expeditiously lowered into a well bore and anchored at any desired point therein, which whipstock can be easily and quickly removed from the well bore after it has served its purpose.

10 My present invention contemplates the provision of a whipstock body having the usual inclined bit-deflecting surface. Mounted on this body is a normally ineffective clutch for anchoring the body to the casing in which it is run.

15 This clutch can be rendered effective at any point in the casing so that the body can be anchored therein at the desired location. After the whipstock has served its purpose, the clutch means may be disengaged and the whipstock may

20 be removed from the hole.

One form which the invention may assume is exemplified in the following description and illustrated by way of example in the accompanying drawings, in which:

25 Fig. 1 is a composite view showing all of the various parts of the apparatus, except the clutch, embodying my present invention, with various of the parts in section to more fully disclose certain features of construction.

30 Fig. 2 is a fragmentary view of the whipstock body and setting tool partially in elevation and partially in section to show the manner of attachment between the tool and the whipstock body.

35 Fig. 3 is a view similar to Fig. 2 except that it discloses the manner of disconnecting the setting tool from the whipstock body.

Fig. 4 is a fragmentary view in elevation and section showing the mounting of the clutch thereon in the position it assumes when the whipstock is being run in or being pulled out of the hole.

Fig. 5 is a view similar to Fig. 4 except that it discloses the clutch in anchoring position.

40 Fig. 6 is a view like Fig. 5 except that it discloses the clutch in side elevation.

Figs. 7 and 8 are end views of the clutch showing the same both in expanded and contracted condition.

45 Referring more particularly to the accompanying drawings, 10 indicates my improved whipstock apparatus which includes a whipstock body 11 having the usual wedge-shaped portion providing the inclined deflecting surface 12. Forming a fixed part of the whipstock body and depending

therefrom is a tapered mandrel 14 having four fixed feather keys 15 arranged longitudinally.

Slidably mounted on the mandrel 14 and bored complementary thereto is an expansible anchoring clutch 16. This clutch is formed in four complementary segments each having a featherway 17 slidably engaging one of the feather keys 15. Circular contractile elastic bands 18 circumscribe the clutch 16 and constantly tend to maintain the clutch contracted about the tapered mandrel, although permitting the same to be expanded. The outer surfaces of the anchoring clutch are provided with gripping means 19 to grip the casing, when expanded, into contact therewith.

The whipstock body and tapered mandrel are 15 formed with a coaxial bore 20. A shaft 21 is reciprocably mounted in said bore and is feathered therein against rotation. The upper end of the bore is counterbored as at 22 to provide an annular shoulder 23. The upper end of the shaft 21 20 is enlarged so as to fit the counterbore and to be shouldered on the shoulder 23. The upper end of the shaft is obliquely cut off so that when shouldered on the shoulder 23, its oblique surface will coincide with the deflecting surface of the 25 whipstock body as illustrated. The shaft 21 is somewhat longer than the bore 20 in the body and in the mandrel so that normally it will project a distance below the lower end of the mandrel 14 as shown in Figs. 1 and 4. At its lower extremity 30 the shaft is fitted with a fixed cup member 24 to embrace the lower ends of the clutch as illustrated.

At the upper end of the whipstock body is formed an obliquely arranged socket 25 to be detachably engaged by a hook 26 on the lower end of a lowering line 27.

Extending inwardly from the oblique surface 21a of the shaft 21 is a socket 28 to be engaged by a pivotal dog or hook 29 carried by a wedge-shaped setting tool 30 attached to the lower end of a line 31. By means of the socket 28 and hook 29 the setting tool 30 may be connected to or disconnected from the whipstock body, as will be described.

45 In operation of my improved apparatus, it is constructed substantially as described herein and illustrated in the drawing, and assembled for running in the hole with the clutch in the position shown in Fig. 4 and with the setting tool 50 connected with the whipstock body through the medium of the socket 28 and hook 29, as illustrated in Fig. 2. It is then lowered into the well bore with the principal weight of the device on the running in line 27, but with the line 31 under

tension, so as to prevent the setting tool 30 from becoming disengaged from the whipstock body. When the apparatus has reached a predetermined position within the casing, the weight is shifted 5 from the line 27 to the line 31 so that the entire weight of the apparatus is borne on the line 31.

It will be noticed that the hook or dog 29 cannot become disengaged from the socket 28 under such circumstances because the socket 28 will 10 prevent pivotal movement of the hook as is clearly evidenced from Fig. 2. That is to say, the setting tool 30 must be lowered relative to the socket 28 in order that the dog or hook 29 may be disengaged from the socket.

15 Immediately the weight is transferred from the line 27 to the line 31, the whipstock body will lower, forcing the tapered mandrel 14 into the clutch 16, expanding the same into gripping engagement with the well casing inasmuch as the 20 whipstock body may move downwardly due to its weight, while the shaft 21 remains stationary.

After the clutch has been expanded into gripping or anchoring position, it may be further set by raising the wedge member and consequently the shaft by means of the cable or line 31 and then allowing the same to fall, drivnig the mandrel further through the clutch and setting it tighter against the casing wall. When the whipstock body is so anchored, the cable 27 30 may be disengaged by merely allowing it to slacken, disengaging the hook 26 from the socket 25, and the setting tool may be disengaged from the shaft 21 by allowing it to lower relative to the socket 28, which lowering movement will 35 enable the weighted pivotal pawl to swing to an unobstructing position as shown in Fig. 3. Thereafter the setting tool may be removed from the hole.

In order to remove the whipstock from the 40 hole after it has served its purpose, the hook 26 may be lowered into the hole on the line 27 and engaged with the socket 25 in the whipstock body. Thereafter a pull exerted on the running in line 27 will cause the tapered mandrel 14 to 45 be pulled out of the clutch 16 so that the contractile band 18 may collapse the same to an ineffective condition. A continued pull on the line 27 will then remove from the hole the whipstock body 11, the mandrel 14 and the clutch 50 16 so that drilling operations may be proceeded with.

While I have shown the preferred form of my invention, it is to be understood that various changes may be made in its construction by those skilled in the art without departing from

the spirit of the invention as defined in the appended claims.

Having now described my invention what I claim and desire to secure by Letters Patent is:—

1. In combination a well casing, a whipstock 5 consisting of a tool deflector, a clutch attached to said deflector, detachable means actuated at the surface to lower said whipstock into the bore, means to actuate from the surface said clutch to grip the casing, means actuated at the surface 10 to release said clutch from its grip in the casing, means at the surface to form attachment to the whipstock whereby it may be raised out of the bore.

2. In combination a well casing, a whipstock 15 including a tool deflector, a tapered mandrel attached to said deflector, segmental clutch members surrounding said mandrel, means actuated at the surface to force said mandrel axially between said segmental clutch members to grip said 20 casing, means actuated at the surface to withdraw said mandrel axially from said segmental clutch members whereby to release said clutch from its grip in the casing.

3. In combination a well casing, a whipstock 25 consisting of a tool deflector, a casing clutch attached to said deflector, means at the surface to actuate said clutch, means at the surface to release said clutch, means to prevent said deflector from rotating about its longitudinal axis when 30 said clutch is at grips with the casing.

4. In combination a well casing, a whipstock having means to lower said whipstock into the bore to any desired location, means to disengage 35 said lowering means, means to firmly clutch said whipstock to the casing, means to disengage said clutch actuating means and remove it from the bore, means to reengage said clutch actuating means and to release said clutch from its grip on the casing, means to reengage said whipstock 40 lowering means whereby said whipstock may be hoisted out of the bore, all of said means being under control of an operator at the surface.

5. In combination with a well casing, a whipstock including a whipstock body having an inclined deflecting surface, a tapered mandrel depending from said body, a normally contracted expandible clutch surrounding said mandrel, means actuated at the surface to force said mandrel axially through said clutch to expand the 45 same and thereby grip the casing, and means actuated at the surface to withdraw said mandrel axially from said clutch to enable the same to contract and release its grip with the casing.

CLINTON L. WALKER.
